CLAIM

The ornamental design for a light bulb, as shown and described.

DESCRIPTION

FIG. 1 is a side perspective view of a first embodiment of a light bulb;

FIG. 2 is a bottom perspective view of the embodiment shown in FIG. 1;

FIG. 3 is a side view of the embodiment shown in FIG. 1;

FIG. 4 is another side view of the embodiment shown in FIG. 1;

FIG. 5 is a top view of the embodiment shown in FIG. 1; and,

FIG. 6 is a bottom view of the embodiment shown in FIG. 1.

The subject matter shown in broken lines is environmental and forms no part of the claimed design.
